UNITED STATES PATENT OFFICE

ROY T. HURLEY, OF DOBBS FERRY, AND WILLIAM J. CARRY, OF BROOKLYN, NEW YORK,
ASSIGNORS TO GENERAL BRONZE CORPORATION, OF LONG ISLAND CITY, NEW YORK,
A CORPORATION OF NEW YORK

WINDOW CONSTRUCTION

Application filed December 8, 1930. Serial No. 500,909.

This invention relates to a window construction and has for an object to provide a constructional element with novel characteristics adapted to be made in a novel way and 5 adapted to be utilized in the construction of windows of various types.

A further object of the invention is to provide a sash construction utilizing such novel element and which will be attractive in appearance, economical to manufacture and 10 strong and durable in use. Sashes embodying the novel constructional element may be mounted in any of the manners customary in window construction, but are more particularly 15 adapted for use in sliding-sash windows, and in the present specification the invention is described and illustrated in connection with a double hung, sliding-sash window, but it is to be understood that the invention in its broader aspects is not limited to such a type of window.

It is a particular object of the invention to provide a window and elements for constructing the same characterized by the use of sheet 20 metal, preferably a non-corrosive metal such as aluminum or aluminum alloy, rolled or bent to proper cross-section and welded into a firm tubular construction by means of a weld which shall be located in a position where it 25 shall normally be concealed from view and shall not interfere with the proper operation of the window.

An aluminum alloy containing five to 30 twelve per cent silicon is the most preferred material since an alloy of such composition combines the desired qualities of lightness, strength, stiffness, and resistance to corrosion and is well adapted for welding, being highly fluid when fused. Such alloy is less subject to corrosion at the welding operation 35 than other aluminum alloys or unalloyed aluminum. For bronze windows a silicon manganese bronze alloy is preferred.

Referring more particularly to sliding-sash windows, it is a feature of the invention 40 that the principal parts of the sashes, namely, the upper and lower rails and the stiles thereof, are formed from sheet metal, preferably sheet aluminum, rolled to the desired shape 45 and welded to form tubing, the weld seams

of the stiles being so located that they are concealed in the finished sash yet do not interfere with the sliding thereof, and therefore may be left as raw seams. The fact that the seams 55 may be left raw gives assurance of adequate strength along the seams in the finished product since no metal is removed at or adjacent to the seams.

A further feature of the invention has to do with the method and means of uniting the 60 upper and lower sash rails with the stiles and particularly of reinforcing these unions.

Other objects and advantages will herein-after appear.

In the drawings forming part of this specification:

Figure 1 is a vertical, sectional view taken through a window embodying features of the invention, the section being taken on the line 1—1 of Figure 3, looking in the direction of 70 the arrows;

Figure 2 is an end view of a piece of sheet metal rolled into tubular form for use in making the meeting rail of the upper sash;

Figure 3 is a horizontal sectional view 75 taken on the line 3—3 of Figure 1, looking in the direction of the arrows;

Figure 4 is a fragmentary, detail view of an upper corner of a sash, partly broken away for purposes of illustration;

Figure 5 is a fragmentary, end view of the sash corner illustrated in Figure 4;

Figure 6 is a sectional view on the line 6—6 of Figure 4, looking in the direction of the arrows;

Figure 7 is a sectional view on the line 7—7 of Figure 4, looking in the direction of the arrows;

Figure 8 is a detail view of a weight chain 90 clip employed at the upper corners of the sashes;

Figure 9 is a perspective view of a reinforcing corner block employed at the upper corners of both the upper and lower sashes;

Figure 10 shows end views of the tubular 95 members employed in making the upper rail of the lower sash;

Figure 11 is a fragmentary, vertical, sectional view through a lower corner of the lower sash, the view being taken on the line 100

11—11 of Figure 12, looking in the direction of the arrows;

Figure 12 is a fragmentary, sectional view of a lower corner of the lower sash, the features illustrated, however, being common to the lower corners of both sashes;

Figure 13 is a fragmentary view illustrating the method of welding the tubular members which are to form the rails and stiles;

10 Figure 14 illustrates a further step in the manufacture of these members into pieces adapted to be employed in window sashes; and

15 Figure 15 is a perspective view of a corner bracket as used for bracing the lower corners of both sashes.

The upper and lower sashes 1 and 2 are illustrated as mounted in a window frame 3. The window frame structure is desirably, 20 though not necessarily, like that disclosed and claimed in my pending application Serial No. 500,908, filed December 8, 1930. The frame includes a removable, vertical parting strip 4, and a removable, vertical inside retaining 25 strip 5, so that upon removal of these strips the sashes may be swung inward and taken out of the frame when desired. The parting and retaining strips referred to, together with an outside retaining strip 6, define vertical guide channels for the upper and lower 30 sashes in which the sashes are slidable.

The upper and lower sashes are generally alike with the exception of such differences as minor differences in cross sectional shape, 35 the provision and location of coacting locking parts and the provision of a sash lift on the lower sash. They may, therefore, be generally covered by a common description. This description will be directed to the lower 40 sash and the differences between the lower and the upper sashes will then be pointed out.

The lower sash comprises a bottom rail 7 formed of sheet aluminum or other suitable sheet metal which is rolled into tubular form 45 of the cross sectional shape illustrated in Fig. 13. It will be noted that this tubular member is formed with an external groove 8 in one face thereof for receiving and supporting a pane 9, and that on the back side opposite said groove the marginal portions of the sheet are caused to form a shallow, broad, 50 external depression 10. The edges of the sheet are brought together at the middle of this depression, and the edge portions are 55 folded outward a short distance to form short abutting flanges 11. These flanges terminate below the surfaces 12 of the tubular member 7. The member 7 is next welded continuously along the flanges 11 to unite them and thereby form a strong, substantially rigid tube; a suitable flux F being utilized as a part 60 of the welding process if necessary. The tubular member 7 is cut at such points that the member is divided into suitable lengths 65 for forming bottom rails of windows of pre-

determined dimensions. Preferably the ends of the lengths are mitered so as to form mitered joints with the stiles. The bottom rail member 7 thus formed is next slit for a short distance from the corners, as shown at 13 in Fig. 14, preferably along the welded seam by means of a cutter 14. The purpose of this slitting will be made apparent presently.

The sash stiles 15 are made of sheet metal, such as aluminum, and are formed, welded, 70 mitered, and slit in the manner already described in connection with the bottom rail. They are preferably identical in cross sectional shape with the bottom rail, particularly in the provision of the wide, shallow 80 recess 10 and the welding seam 16 located substantially at the middle of this recess. It is a point of prime importance that this weld seam of the sash stile is located at the concealed side of the stile, and that it is positioned in a recess so that it safely clears the base of the sash channel-guide of the frame. Because the weld seam is not seen and because it is so spaced from the bottom of the 85 guide channel of the frame as to clear it, it is unnecessary to grind or polish this seam, and hence the same may be left raw. A saving is thus effected in producing a suitably finished sash, and as a result of the same feature all possibility of weakening the seam by grinding is obviated. The raw weld seam definitely and reliably provides a lighter and stronger construction than could be secured with other types of seam, such for example 95 as a lock-joint seam.

The location of the welded seam at the back or outside of the sash elements is important for the reason stated, namely that the seam is normally hidden and can be kept out of contact with the adjacent window frame elements by the formation of a depression in which the weld is located. This location of the welded seam is also desirable as it is possible to provide a fairly wide depression at this point which permits of greater freedom for the carrying on of the welding operations. For instance, if a gas flame be used for the welding, it need not be confined within extremely narrow limits, nor need the finished weld be held to highly restricted dimensions. The location of the welded seam along the part of the window element which will lie in a plane parallel with the plane of the window, is also highly desirable as it makes possible the carrying out of the welding operation without any tendency to produce such a distortion of the welded tube as would tend to cause a lateral warping of the window. This is particularly 105 the case if the seam is welded at or near the medial plane of the window, in which event there is no tendency for lateral distortion at all, any tendency for distortion of the tube being in planes which will lie parallel 110 to the plane of the finished window when the 115

tube is assembled therein. Any tendency for distortion in such a plane is adequately taken care of when the elements are assembled into the completed sash.

- 5 The mitered stiles are united with the mitered bottom rail by welding along the meeting mitered edges, that is to say, a weld seam is formed along the line 17 of Fig. 11. The sash corner is further reinforced, however, to make sure that the sash may not be distorted out of its rectangular shape by the provision of a reinforcing angle bracket 18 at the corner. These brackets 18 are preferably made of flat sheet metal and therefore are of the cheapest possible construction, the desired rigidity being secured however by mounting them edgewise in the manner to be described. It is for the purpose of receiving and cooperating with the reinforcing bracket 18 that the tubular members 7 and 15 are slit adjacent their mitered ends after they have been welded into tubular form. The angle bracket 18 is slipped into the two parts to be joined as seen in Fig. 12, and these parts are then joined by welding, the seam being welded first along the outer edges 19 and 20 of the angle bracket. These edges stand substantially flush with, or protrude a little beyond, the faces of the stile 15 and the bottom rail 7 adjacent the slits 13. The seams thus welded, however, lie within the channels 10 of the bottom rail and the stiles. The reinforcing angle brackets 18 are preferably notched at the outer end corners to provide inset edges 21 and 22 adapted to fit snugly within the stile 15 and the bottom rail 7. After the seams have been welded along the edges 19 and 20, the seam is welded along the line 17 of Fig. 11.
- 40 While any suitable construction may be utilized for mounting the glass panes, in the particular construction illustrated, it is intended that the window pane 9 shall be slideable into the sash through the upper rail thereof. The upper rail is not therefore made in the same way as the bottom rail and the stiles. The upper rail 23 comprises inside and outside tubular members 24 and 25 which are rolled from sheet metal to the respective forms shown in Fig. 10. In each instance the meeting edges are welded together by a longitudinal seam and are then ground to provide flush faces for engagement with the window pane. The lengths of these tubular members are subsequently mitered to divide them into pieces of appropriate length for making sashes of the desired dimensions and to adapt them to fit accurately with the stiles.
- 80 Provision is made of blocks 26 (see particularly Fig. 9) adapted to be fitted into the upper ends of the stiles and to interfit with the mitered ends of the tubular members 24 and 25, correctly spacing them from one another and locating them in registration with the corresponding parts of the stiles. The

block 26 is provided with a rib 27 on the outer face thereof adapted to fit through the slit in the upper end of the outer wall of the stile and to be welded to the stile. It is also provided at its upper end with slots 28 and 29 for receiving the ends of the inside walls of the members 24 and 25. The members 24 and 25 are welded to the stiles along the line 30 (see Fig. 4). After the window pane 9 has been inserted in the sash constructed as thus far described, a bar 31 having a dovetailed groove 32 therein is slid onto the top rail to embrace the upper portions of the members 24 and 25. The dovetailed groove 32 interfits with the dovetailed projection 80 formed jointly by the upper portions of the members 24 and 25. The end portions of the bar 31 overlie the blocks 26 and are removably secured to them by screws 33. The outer extremities of the bars 31 are provided with notches 34 for a purpose which will presently be brought out.

The bar 31 is provided with a tongue 31a adapted to extend between the tubular members 24 and 25 and serve as a spacer between them. Thus, when the bar 31 is slid onto the members 24 and 25 the tongue which is at least as broad as the thickness of the window pane prevents the application of pressure and of bending strains to the pane and thereby protects the pane against breakage.

The block 26 has a recess 35 in the upper portion of the outer face thereof which is adapted to receive a sheet metal clip 36 whereby the sash is secured to a weight chain. This stirrup consists of a sheet metal member split along its center to provide a plurality of legs 37 and 38 and having an eye 39 at the junction of the legs to receive a chain link. The clip 36 may have a chain link 40 slid over one leg thereof and fitted into the eye. The legs 37 and 38 may then be brought to a common plane and may be slid down into the recess 35 of the block 26 until screw openings 41 in the clip 36 come into registration 100 with screw holes 41a in the block 26. In this position the clip is removably secured to the block by screws 42 inserted through openings 43 in the stiles and threaded into the screw holes in the block. In this position the clip 36 is positioned entirely below the top of the block 26 so that it does not interfere with sliding of the bar 31 when it is desired to remove the bar 31 for permitting the insertion or replacement of the window pane. Such replacement of the window pane may be effected by separating the removable retaining rail from the frame, swinging the window inward, removing the screws 33 that fix the bar 31 in place, bending the chain clear 125 of the path in which the bar 31 will slide, and then withdrawing the old pane or fragments thereof and inserting a new one.

The description up to this point is applicable to the lower sash and to the upper sash 130

alike. In the case of the lower sash, however, a weather strip 44 of spring metal is welded or otherwise fastened at intervals to the under sash of the bottom rail and curls 5 around the edge thereof to cooperate with the sill when the window is closed. A lip 44a at the eye of the weather strip engages the edge of the sash rail and supports the flange of the weather strip, thus assuring a firm but 10 resilient engagement between it and the sill when the window is closed. A sash lift 45 is also welded to the lower rail of the lower sash. The lower rail of the upper sash is of slightly different cross sectional shape in 15 that provision is made of a recess in the inner face of the rail to which a weather strip 45a of spring metal is welded or otherwise fastened at intervals, this weather strip being designed to coat with the outer face of the 20 upper or meeting rail of the lower sash. The bar 31 of the lower sash has a lock base 46 welded to it on which a bolt member 47 is pivoted, and the lower rail of the upper sash has a keeper member 48 welded to it for co- 25 action with the bolt 47.

Wherever exposed welds occur, particularly in the inner faces of the sashes, these welds are preferably ground and polished, so that in the finished window it cannot be 30 seen that the top and bottom rails and the stiles are not integral.

Not only is the sash as described of very light construction because of the lightness of the metal or the metallic alloy employed, 35 but the parts are all constructed and designed to provide adequate strength and rigidity with the minimum utilization of material. The result is that the described sash is considerably lighter than sashes of equivalent 40 strength heretofore produced. This saving of weight is important not only in the sash itself, but in the fact that any saving of weight effected in the sash makes possible an equal saving in the counter-weights. Because 45 of the lightness and strength of the described sash, it is adapted to be shipped to any point near or distant, and even overseas, the cost of adequately protecting it by packing being slight, and the cost of transportation being 50 low.

While we have illustrated and described in detail certain preferred forms of our invention, it is to be understood that changes may be made therein and the invention embodied 55 in other structures. We do not, therefore, desire to limit ourselves to the specific constructions illustrated, but intend to cover our invention broadly in whatever form its principle may be utilized.

60 What is claimed is:

1. A one piece sheet metal stile or rail tubing for windows, having a pane seat at one side thereof, and having a longitudinal, channel-shaped depression formed in the opposite side, the longitudinal edges of the

sheet being brought together in said depression, and a weld seam uniting said edges.

2. A one piece sheet metal stile or rail tubing for window sashes, having a side thereof which will be concealed when the sash is finished and installed, formed with a broad, shallow, longitudinal, channel-shaped depression, and having the longitudinal edges of the sheet brought together in said depression, and a raw weld seam uniting said edges. 70

3. A one piece sheet metal stile or rail tubing for window sashes, having a side thereof which will be concealed when the sash is finished and installed, formed with a broad, shallow, longitudinal, channel-shaped depression, and having the longitudinal edges of the sheet brought together in said depression, and a raw weld seam uniting said edges, the weld seam being entirely contained within 80 in said depression.

4. A one piece sheet metal stile or rail tubing for window sashes, having a side thereof which will be concealed when the sash is finished and installed, formed with a longitudinal, channel-shaped depression, and having the longitudinal edges of the sheet brought together in said depression, and a weld seam uniting said edges, the weld seam being located substantially in the longitudinal median plane of the sash. 90

5. A window sash comprising tubular sheet metal stiles and a tubular sheet metal bottom rail and corner reinforcing angle brackets engaging the inner walls of the adjoining tubular members and projecting through the outer walls of said members and welded to each of said members. 95

6. A window sash comprising tubular sheet metal stiles, and a top rail comprising a plurality of spaced, parallel, tubular sheet metal members welded to the stiles, and reinforcing blocks at the meeting corners of the stiles and the top rail and united to the stiles, said blocks having slots for receiving end portions of the inner walls of the top rail members to locate the outer walls of said members flush with the outer walls of the stiles. 105

7. A window sash comprising tubular sheet metal stiles, and a top rail comprising a plurality of spaced, parallel, tubular sheet metal members welded to the stiles, and a cover bar interlocked with the top rail members but slidably longitudinally thereof, reinforcing blocks at the meeting corners of the stiles and the top rail and united to both the stiles and the top tubular rail members, and flexible weight-carrying members secured to said blocks and swingable to positions to clear the cover bar when the same is slid along the 110 top rail. 115

8. A window sash comprising tubular sheet metal stiles, and a top rail comprising a plurality of spaced, parallel, tubular sheet metal members welded to the stiles, reinforce- 120 130

ing blocks at the meeting corners of the stiles and the top rail and united to both the stiles and the top rail, a grooved cover bar interlocked with the top rail tubing, and removable means connecting the cover bar with the blocks.

9. The method of making window sashes, which comprises shaping a sheet of metal to tubular form with a pane seat in one face thereof, and a depression in the opposite face, and with the longitudinal edges of the sheet brought together in said depression, continuously uniting said longitudinal edges by welding, cutting the tubing into appropriate lengths on a bevel, slotting the tubing along the base of the depression for a distance inward from the bevel cuts, placing an angled reinforcing member in the slots of tubing members to be joined, and welding the tubing members to the reinforcing member.

10. The method of making window sashes, which comprises shaping a sheet of metal to tubular form with a pane seat in one face thereof, and a depression in the opposite face, and with the longitudinal edges of the sheet brought together in the center of said depression, continuously uniting said longitudinal edges by welding, cutting the tubing into appropriate lengths on a bevel, slotting the tubing along the central portion of the depression for a distance inward from the bevel cuts, placing an angled reinforcing member in the slots of tubing members to be joined, and welding the tubing members to the reinforcing member.

11. The method of making window sashes, which comprises shaping a sheet of metal to tubular form with a pane seat in one face thereof, and a depression in the opposite face, and with the longitudinal edges of the sheet brought together in said depression, continuously uniting said longitudinal edges by welding, cutting the tubing into appropriate lengths on a bevel, slotting the tubing along the base of the depression for a distance inward from the bevel cuts, placing an angled reinforcing member in the slots of tubing members to be joined, and welding the tubing members to the reinforcing member, and directly to one another.

12. In a window sash, in combination, a tubular bottom rail, a tubular stile, and a flat corner-reinforcing angle bracket placed edgewise in said tubular members in the longitudinal median plane of the sash in engagement with the inner and outer walls of said members and welded to the outer walls.

13. In a window sash, in combination, a tubular bottom rail, a tubular stile, and a flat corner-reinforcing angle bracket placed edgewise in said tubular members in engagement with the inner faces of the inner and outer walls thereof, and having portions extended through the outer walls and welded to them.

In testimony whereof we have affixed our signatures to this specification.

ROY T. HURLEY.
WILLIAM J. CARRY.
